UNITED STATES PATENT OFFICE.

JAMES HENRY SWINDELL, OF ATLANTA, GEORGIA.

ENVELOP.

1,012,112.

Specification of Letters Patent. Patented Dec. 19, 1911.

Application filed August 17, 1909. Serial No. 513,324.

To all whom it may concern:

Be it known that I, JAMES H. SWINDELL, a citizen of the United States, residing at Atlanta, in the county of Fulton and State of Georgia, have invented a new and useful Envelop; and I do hereby declare the following to be a full, clear, and exact description of the invention, such as will enable others skilled in the art to which it appertains to make and use the same.

This invention relates to a new and useful envelop.

The main object of the invention is to provide an improved device of this nature, so constructed that the same cannot be unsealed and opened without detection.

Another object of the invention is to provide an envelop having a bottom flap, the end portion of which is folded upon itself, for reinforcing a strap (which is defined by long and short registering slots in the folded portion) of the bottom flap. The closure flap (which is provided with a tip gummed on both sides thereof) is designed to be passed through the slots, with the tip folded back over the strap and secured between the strap and the closure flap. The envelop is provided with side flaps, upon one end of each of which the closure flap is folded.

A further object of the invention is the provision of an envelop adapted particularly for use, where large envelopes are required, thus cheapening the same by eliminating the usual metal clamp or rivet generally used.

The invention comprises further features and combination of parts, as hereinafter set forth, shown in the drawings and claimed.

In the drawings:—Figure 1 is a view in perspective of an envelop constructed in accordance with the invention. Fig. 2 is a plan view of the envelop showing the closure flap and the tip as passed through the slots beneath the strap. Fig. 3 is a view similar to Fig. 2, showing the tip folded back over the strap and secured between the strap and the closure strap. Fig. 4 is a sectional view on line 4—4 of Fig. 3. Fig. 5 is a plan view of the blank of the envelop.

Referring more especially to the drawings 1^a designates the addressed portion of the envelop. The addressed portion of the

envelop is provided with side flaps 1^b, a bottom flap 1 and a closure flap 5. The bottom flap 1 is folded upon itself at the point 55 designated by the character 1^c, thus providing a reinforcing section 2 for the bottom flap. The reinforcing section 2 is provided with slots 3 and 4, as shown clearly in Fig. 5. The reinforced portion 2' of the bottom flap (which is folded upon the addressed portion 1^a when the envelop is constructed) is provided with a strap 7, which is defined by the slots 3' and 4'. The slots 3 are longer than the slots 4. The closure flap 5 is provided with an extension tip 6, the free portion of which is gummed on both sides.

When constructing an envelop of this nature, the bottom flap is folded upon itself at the point 1^c, so that the slots 3' and 4' in the body of the bottom flap and the slots 3 and 4 in the folded portion are brought into registration, thus forming a reinforced portion for the bottom flap. The bottom flap is then folded at ^a upon the addressed portion 1^a, then the side flaps 1^b are folded over and gummed to the bottom flap. The closure flap 5 is left free, until the envelop is desired for use.

When it is desired to seal the envelop, the closure flap with its tip 6 is first passed through the slot 3 and then through the slot 4, as shown in Fig. 2. In folding the closure flap the same folds upon one end of each of the side flaps, as shown at 8 in Figs. 2 and 3. The extension tip 6 is subsequently folded back over the strap 7, as shown in Figs. 3 and 4, and finally secured between the strap 7 and the body of the closure flap.

The invention having been set forth, what is claimed as new and useful is:—

A safety envelop comprising a body portion having bottom and closure flaps, and side flaps folded upon and secured to the bottom flap along its sides, said bottom flap being folded upon itself adjacent the mouth of the envelop, with the folded portion beneath the side flaps, registering slots cut in said folded portion and the bottom flap forming a strap between the slots, one of the registering slots being long and the other short, said closure flap having an extension tip gummed on both sides thereof, said closure flap and the extension tip adapt-

ed to pass through the long and short registering slots and beneath the strap, which is defined by the slots, with the extension tip folded back over the strap, and finally inserted in the long registering slots, and secured between the strap and the main portion of the closure flap.

In testimony whereof I have signed my name to this specification in the presence of two subscribing witnesses.

JAMES HENRY SWINDELL.
